UNITED STATES PATENT OFFICE.

CHARLES M. GOLDSTEIN, OF NEW YORK, N. Y., ASSIGNOR TO COLUMBIA GRAPHOPHONE MANUFACTURING COMPANY, OF BRIDGEPORT, CONNECTICUT, A CORPORATION OF DELAWARE.

PHONOGRAPHIC MACHINE.

1,408,585.

Specification of Letters Patent.

Patented Mar. 7, 1922.

Application filed April 10, 1920. Serial No. 372,745.

To all whom it may concern:

Be it known that I, CHARLES M. GOLDSTEIN, a citizen of the Republic of Germany, residing at New York, in the county of New York and State of New York, have invented certain new and useful Improvements in Phonographic Machines, of which the following is a full, clear, and exact description.

My invention relates to phonographic machines of the type used for dictation purposes. In machines of this character the spoken words are engraved by a vibrating stylus in a wax tablet which is usually in the form of a cylinder. If reference is desired to be made to the engraved words for any purpose, as by noting that a correction should be made at a certain point, additional spoken words are recorded to that effect and a signal for the benefit of the transcriber made at the point of desired correction.

This signal ordinarily includes a card having a printed scale corresponding in graduations with that on the machine and along which a pointer travels in unison with the supporting carriage of the sound-box, so that a mark or check at a point on the card scale will call attention to a correction at a corresponding point in the wax tablet.

Various devices for incorporation into the machine have been proposed for facilitating the making of said signals. These devices, however, usually necessitate considerable redesigning of the phonographic machine. Others have the objection of contributing to a complicated appearing machine,—a condition which is not desirable in phonographic machines.

My invention aims to improve devices of the character indicated by making the indicating device susceptible of attachment to existing machines without necessitating structural rearrangements therein.

Another object of my invention is to provide mechanical marking means in combination with an index sheet arranged in the form of a cylinder.

Another object of my invention is to embody the above feature in a pleasing mechanical arrangement. The importance of this feature will be more fully appreciated when it is borne in mind that the machine is always in full view of the user. Other minor ob-

jects will appear from the detailed description of the invention.

My invention consists, briefly, in mounting a cylinder or barrel on the sound-box carriage for travel therewith and providing means for rotating it as the carriage travels. The cylinder is adapted to receive an index sheet on which indications are adapted to be made to indicate various points in the engraved sound tablet. In fixed relation to the axis of said cylinder I mount a bracket which overhangs the cylinder and is provided with openings which serve as guides for means adapted to make contact with the index sheet on the cylinder. These means preferably take the form of pointed, axially movable prick punches. The cylinder is preferably mounted on the sound-conducting head of the travelling carriage and the means for rotating it preferably comprise a rack and pinion connection so arranged that the cylinder may be rotated counter-clockwise.

One of the advantages resulting from mounting the index sheet on a cylinder as said is that there is only a relatively small portion of said sheet adjacent said pointer at any given time on which check marks can be conveniently entered when not mechanically performed. In other words the index sheet slopes downwardly on either side of the pointer resulting in a relatively raised portion adjacent said pointer. When it is remembered that the index sheet is graduated in a manner corresponding to the scale on the machine and that these sheet graduations are automatically presented in front of the pointer as the carriage travels, it will be readily appreciated that very little or no opportunity is presented for the incorrect transference thereto of the scale-pointer readings. As already indicated, however, I prefer to provide mechanical marking means.

In the drawings which illustrate the preferred form of the invention,—

Fig. 1 is a vertical section taken on line 1—1 of Fig. 3, sufficient parts of a phonographic machine being illustrated to show the application of my invention;

Fig. 2 is a front elevation of my invention looking in the direction of the arrow "2" in Fig. 1, the mechanical marking means being omitted;

Fig. 3 is a top plan of Fig. 1, looking in the direction of arrow "3";

Fig. 4 is a vertical section taken on line 4—4 of Fig. 1;

Fig. 5 is a section taken on line 5—5 of Fig. 6;

Fig. 6 is a top plan of Fig. 5, parts being broken away and parts being in section; and

Fig. 7 is a section on line 7—7 of Fig. 4;

In the drawings, only so much of the phonographic machine is shown as is necessary to illustrate the application of my invention thereto.

The base 10 of the machine rests on a motor box 11 in which is contained mechanism (not shown) for rotating the record tablet 12 and for moving the sound-box carriage 13 longitudinally thereover. The tablet 12 is mounted for rotation in any suitable or preferred manner.

Rising from the base of the machine at either end thereof is a pair of standards 14, 15. Extending between these standards is a slotted tube 16, along which the carriage 13 is movable. This tube is adapted to contain a screw shaft (not shown) for causing travelling movement of said carriage axially of the cylindrical tablet 12 upon the suitable manipulation of the lever 17, which serves to operatively connect the carriage to said screw shaft. The carriage is prevented from rotating on said tube 16 by means of a stabilizer arm 18 which is bifurcated at its lower end to straddle a rod 19 extending between the said standards. Along said tube and rod the carriage may be freely moved by hand when the lever 17 is in neutral position.

Extending forwardly from each standard at the top thereof is a support 20 for supporting a bar 21 which carries a scale 22. Rising from the carriage 13 in close proximity to the said scale is a pointer 23.

Incorporated in the carriage is a suitable sound-box 24 which is adapted to be connected to a speaker's tube (not shown) by a cored head designated generally by numeral 25.

The construction thus far described is the usual and familiar construction of a dictation machine well known in the art.

In giving a mechanical embodiment to my invention, I mount a cylinder 26 on the head 25 in a manner which permits its rotation thereon. I prefer to effect this mounting by providing a suitable bearing in the form of a sleeve 27 which at its outer end is internally tapered and threaded to receive a complementary tapered and threaded split bushing 28 which serves to lock the sleeve 27 to said head. The cylinder is held against axial displacement by any suitable means, as by a hidden, expansible ring 29 confined in an annular groove formed in the cylinder and sleeve in a manner well known in the art.

This arrangement permits of easy and ready assemblage by permitting the cylinder to be slipped over the sleeve and contributes to a slight machine by the elimination of screws and the like.

Rotation is imparted to said cylinder by means of a rack and pinion connection, the pinion 30 being secured to the cylinder at the inner end thereof, and the rack 31 being secured to the scale bar 21 in a manner not to interfere with the functions of the normally-provided scale and pointer 22 and 23, respectively. The rack comprises a comparatively wide bar having oppositely directed angles at its edges. One of these angles is comparatively short and is provided with teeth which mesh with the pinion 30. The other angle is secured to the bar 21 behind the scale 22 which is thus left visible. In order to provide for the passage of the pointer 23, the rack bar is slotted (see Fig. 3) for a substantial portion of its length.

It will now be appreciated that as the carriage is moved from left to right along its guides 18 and 19, the cylinder 26 will be rotated about its cylindrical axis in a counter clockwise direction. An index sheet, on the surface of the cylinder, having graduations numbered from left to right, will thus present its graduations in synchronism with those of the scale 22. It will be further appreciated that inasmuch as this rotary index sheet is in close proximity to the normally-provided scale and pointer, there is little or no opportunity for incorrect transference to the index sheet of the scale-pointer reading if the mental and manual method of checking is employed. I prefer, however, to employ mechanical marking means for checking or marking the index sheet.

The mechanical marking means preferably take the form of depressible prick punches 32 which are mounted in tubular guides 33. These guides, which overhang the cylinder 26, are supported by an arched bracket 34 on the carriage 13.

Referring to Figs. 4 and 7, it will be seen that the bracket has laterally projecting feet which are secured to the carriage 13 at spaced points thereon. Fig. 7 also shows the head 25 as being a separate element adapted to be held in definite relation to said carriage in any suitable manner, as by screws (one of which is shown in dotted lines in Fig. 1). This bracket it will be observed, rises from the carriage immediately in front of the rack 31 and is so arranged that it may be easily removed or attached without interfering with the other mechanism. The cylinder is adapted to support an index sheet 35 on its surface. For holding the sheet in place on the cylinder there is provided a hinged spring arm 36 which is pivoted to a block 37 set into the outer edge of the cylinder. (See Figs. 5 and 6.) This arm has, at one side

of its pivot, a yieldable extension which is adapted to bear against the supporting block 37 in such manner that the arm is pressed tight against the index sheet. A hump on the arm adjacent its pivot serves to limit its angular movement.

In order to facilitate the placing of the index sheet around the cylinder, I prefer to provide marginal guides 38, 39 on the latter.

10 These guides have a cut-away portion on either side of the arm 36 to permit the introduction and removal of said sheet. To insert a sheet it is simply necessary to insert one end of the same in the guides and push 15 the sheet on through until their ends overlie, as in Fig. 6, when the spring arm is brought down upon them.

When a prick punch is used for making marks in the index sheet, I prefer to provide 20 a narrow annular groove 40 in the cylinder for receiving the point of the punch as it passes through the sheet.

The invention has been described in considerable detail but this is not to be taken 25 as a limitation of the invention, the scope of which is intended to be set out in the claims.

What I claim as new and desire to secure 30 by Letters Patent is:

1. In a phonographic machine, the combination with the travelling sound-box carriage thereof having a cored head adapted to be connected to a speaker's tube, of a cylinder mounted on said head, and means for imparting rotation to said cylinder during the travel of said carriage.

2. In a phonographic machine, the combination with the travelling sound-box carriage thereof having a cored head adapted 40 to be connected to a speaker's tube, of a cylinder mounted on said head, means for imparting rotation to said cylinder during the travel of said carriage, and marking means movable toward and from said cylinder.

45 3. In a phonograph, the combination with the traveling sound-box carriage thereof having a cored head adapted to be connected to a speaker's tube and a stationary scale-bar disposed longitudinally of the line of travel 50 of the carriage; of a cylinder journaled on said head, and means for imparting rotation to said cylinder during the travel of said carriage and comprising a rack secured to said scale-bar and extending longitudinally of the line of travel of the carriage, and a pinion at one end of said cylinder and meshing with said rack.

55 4. In a phonographic machine, the combination with the travelling sound-box carriage thereof having a cored head adapted to be connected to a speaker's tube, of a cylinder mounted on said head, means for imparting rotation to said cylinder during the travel of the carriage, and a bracket adjacent one end of said cylinder and in fixed rela-

tion to the axis thereof, said bracket carrying marking means movable toward and from said cylinder.

5. In a phonographic machine, the combination with the travelling sound-box carriage thereof having a head adapted to be connected to a speaker's tube, of a cylinder mounted on said head, a bracket secured to said head adjacent one end of said cylinder, and in fixed relation to the axis thereof means carried by said bracket permitting impressions to be made on a suitable surface of said cylinder, and means for imparting rotation to said cylinder during the travel of the carriage.

6. In a phonographic machine, the combination with the travelling sound-box carriage thereof having a cored head adapted to be connected to a speaker's tube, a cylinder mounted on said head, an index sheet adapted to be wound around said cylinder, means for securing said sheet against displacement, and means for imparting rotation to said cylinder during the travel of said carriage.

7. In a phonographic machine, the combination with the travelling sound-box carriage thereof, of a cylinder mounted for travel with said carriage, correction indicating means overhanging said cylinder, an index sheet adapted to be wound around said cylinder, means mounted on said cylinder at one side of said correction indicating means for holding the free end of said sheet against relative displacement, and means for rotating said cylinder during the travel of said carriage to bring said first named means on the other side of said correction indicating means.

8. In a phonographic machine, the combination with the travelling sound-box carriage thereof, of an index sheet, means supporting said sheet in the form of a cylinder, and means for rotating said sheet about its cylindrical axis during the travel of the carriage.

9. In a phonographic machine, the combination with the travelling sound-box carriage thereof, a cylindrical index sheet, means in fixed relation to the axis of said sheet permitting the making of indications on said sheet, and means for rotating the said sheet about its cylindrical axis during the travel of the carriage.

10. In a phonographic machine, the combination with the travelling sound-box carriage thereof, of a cylindrical member mounted to travel with said carriage, means at one end of said cylinder for imparting rotation to said cylinder, and correction indicating means mounted adjacent said end of the cylinder and in fixed relation to the axis thereof.

11. In a phonographic machine, the combination with the travelling sound-box car-

- riage thereof, of a cylindrical member mounted to travel with said carriage, means for imparting rotation to said member, and means disposed in a plane of the axis with 5 relation to the cylindrical member for making indications.
12. In a phonographic machine, the combination with the travelling sound-box carriage thereof, of a cylindrical member 10 mounted to travel with said carriage and adapted to support a correction strip, means for imparting rotation to said member, and means in fixed relation to the axis of said cylinder, for making indications on said 15 correction strip.
13. In a phonographic machine, the combination with the travelling sound-box carriage thereof, of a cylindrical index member adapted to support a cylindrically disposed 20 correction strip upon its cylindrical surface, means for rotating said member synchronously with the travel of said carriage, and means permitting the making of an indication on said correction strip in a fixed 25 position relatively to the cylindrical axis of said member.
14. In a phonographic machine, the combination with the travelling sound-box carriage thereof, of a cylindrical correction 30 strip mounted for travel with said carriage, means for rotating said correction strip as the carriage travels, and means in a fixed position relatively to the axis of said correction strip permitting the making of 35 indications on said correction strip.
15. In a phonographic machine, the combination with the travelling sound-box carriage and scale and pointer thereof, of a member adapted to serve as an index of the 40 sound tablet contents, means for supporting said member in a sloping position on either side of said pointer, and means for imparting relative movement between said pointer and member in synchronism with the travel
- of said carriage whereby a relatively raised 45 portion of said index member is continuously being presented adjacent said pointer.
16. In a phonographic machine, the combination with the sound-box support and record carrier having relative movement between them, of a cylinder adapted to support 50 a correction strip, and means for imparting rotation to said cylinder during the relative movement between the support and the record carrier.
17. In a phonographic machine, the combination with the sound-box support and record carrier having relative movement between them, of a cylinder adapted to support 55 a correction strip, means for imparting rotation to said cylinder during the relative movement between said support and record carrier, and an indicator disposed in indicating relation to a line upon said cylindrical surface parallel to the axis thereof.
18. In a phonographic machine, the combination with the sound-box support and record carrier having relative movement between them, of a cylinder adapted to support 60 a correction strip, means for imparting rotation to said cylinder during the relative movement between said support and the record carrier, and an indicator occupying a fixed position with respect to the cylindrical 65 surface of the cylinder.
19. In a phonographic machine, the combination with the sound-box support and record carrier having relative movement between them, a member mounted to rotate 70 about a fixed axis upon the sound-box support and adapted to support a correction strip cylindrically disposed about said axis, and means for imparting rotation to said member and correction strip during and proportionately to the relative movement between 75 said support and the record carrier.

In testimony whereof, I affix my signature.
CHARLES M. GOLDSTEIN.

Certificate of Correction.

It is hereby certified that in Letters Patent No. 1,408,585, granted March 7, 1922, upon the application of Charles M. Goldstein, of New York, N. Y., for an improvement in "Phonographic Machines," errors appear in the printed specification requiring correction as follows: Page 1, line 70, for the misspelled word "prferably" read *preferably*; page 4, lines 4 and 5, claim 11, strike out the words "with relation to the cylindrical member" and insert the same to follow the word "indications" in line 6; and that the said Letters Patent should be read with these corrections therein that the same may conform to the record of the case in the Patent Office.

Signed and sealed this 24th day of April, A. D., 1922.

[SEAL.]

KARL FENNING,
Acting Commissioner of Patents.
